[57] CLAIM

The ornamental design for an electrical test connector for a printed circuit board, as shown.

DESCRIPTION

FIG. 1 is an exploded perspective view of an electrical test connector for a printed circuit board showing our new design;

FIG. 2 is a perspective view thereof;

FIG. 3 is a top plan view thereof;

FIG. 4 is a right side elevational view thereof;

FIG. 5 is a front elevational view thereof;

FIG. 6 is a rear elevational view thereof;

FIG. 7 is a left side elevational view thereof; and

FIG. 8 is a bottom plan view thereof.

FIG.1

FIG. 3
